UNITED STATES PATENT OFFICE.

HAROLD POTTER DONLE, OF MERIDEN, CONNECTICUT, ASSIGNOR TO THE CONNECTICUT TELEPHONE & ELECTRIC CO. INC., OF MERIDEN, CONNECTICUT, A CORPORATION OF CONNECTICUT.

ELECTRIC-CURRENT-CONTROLLING DEVICE.

Application filed February 2, 1920. Serial No. 355,620.

To all whom it may concern:

Be it known that I, HAROLD POTTER DONLE, a citizen of the United States of America, residing at Meriden, Connecticut, ⁵ have invented a new and useful Electric-Current-Controlling Device, of which the following is a specification.

My invention relates particularly to what is commonly termed a vacuum tube type ¹⁰ of device.

The main object is to provide a simple and compact construction which can be economically and readily manufactured, which will produce a maximum effect with ¹⁵ a minimum power and be durable under normal conditions of use.

Another object is to construct a device which with a small power input will produce relatively great variations of output ²⁰ current.

In its preferred form the tube is of glass and contains a filament having two active portions in series and disposed longitudinally of the tube. This filament constitutes ²⁵ the cathode or emissive element. The anode embraces the tube outside of one portion of the filament and a control electrode or plate embraces the tube adjacent the other portion of the filament. Inside of the tube ³⁰ is an element which may be termed an equalizer, consisting of an annular or cylindrical portion surrounding or partially surrounding one portion of the filament within the influence of the control and cathode, and ³⁵ a connected plexus or network interposed between the other portion of the filament and the anode. The annulus and plexus are electrically connected to each other but not metallically connected to anything else.

The tube when in use is preferably surrounded by a ventilated shield through which the condition of the tube may be observed.

Fig. 1 is a side view of a tube construction embodying my invention with the ventilated shield shown in section.

Fig. 2 is a longitudinal sectional view of the tube itself without the ventilated shield.

Fig. 3 is a transverse sectional view on ⁵⁰ the plane of the line 3—3 of Fig. 2.

Fig. 4 is a transverse sectional view on the plane of the line 4—4 of Fig. 2.

Fig. 5 is a perspective view of the tube itself with its external electrodes.

Fig. 6 is a detail view of the filament and ⁵⁵ its supports.

Fig. 7 is a detail perspective view of the equalizer.

The tube 10 is preferably of transparent glass such as is ordinarily used in the construction of tubes of this general character. It is preferably cylindrical in form and of relatively small diameter and may be provided with an enlarged base 11 with a stem ⁶⁰ 12. I consider that the broad term "tube," ⁶⁵ for the purpose of the claims, covers any shape of bulb or globe.

The internal conductor or cathode has a filament which is preferably composed of two parts 13 and 14 suitably constructed ⁷⁰ to produce a maximum emission. These two parts may be connected by a conductor 15 of less resistance so that the heating effect will be confined to portions 13 and 14. This cathode may be supported by wires 16 and ⁷⁵ 17 embedded in the stem. Preferably, the outer end of the conductor is positive and the inner end negative. The cathode and its supports may be made of molybdenum, tungsten or other suitable metal. The central part of the conductor may be tied to the support 16 by a non-conducting element 18 so as to reinforce the filament.

The anode or plate 19 is preferably in the form of a metallic deposit on the outside ⁸⁰ of the tube surrounding the part 14 of the cathode, near the negative end. I have found silver to be particularly useful for this purpose.

The control electrode 20 is also preferably ⁹⁰ in the form of a similar deposit on the outside of the tube adjacent the filament portion 13 near the positive end. This is shown as a cylinder but it need not be continuous and may have a small area but should closely adhere to the glass.

The equalizer may be made of molybdenum or tungsten or other suitable metal. The annulus or cylinder 21 preferably fits snugly inside of the tube and surrounds the ⁹⁵ 100

filament portion 13. The plexus 22 may be formed of a helix of wire or of a network or perforated screen secured to the connector 23. In the form shown, the equalizer can be readily manufactured and handled as a unit for inserting it in the tube and when inserted, it is supported at its outer end by the contact of the cylinder 21 inside the tube and at its lower end by the tip 12.

10 The electric connections to the tube are effected through the conductors 24, 25, 26 and 27, which may have terminal contacts on the lower end of the tube such as at 28.

15 The tube may be treated as set forth in my application #295,897, filed May 9th, 1919, for increasing the electronic emission.

20 The operation of the equalizer can be described as charging up to negative potential by the accumulation of electrons at the plexus end thereby reducing the emission from the filament at the plexus by repulsion between electrons, and thereafter the modulated dissipation of this negative charge at the other end by the action of varying electrical potentials applied to the control electrode 20. The operation of this tube with the external anode and control, and the internal equalizer is radically different from that of any vacuum tubes heretofore on the market such as the so-called valves and audions.

25 The tube may be used either as a detector, as an amplifier or as an oscillator. It will be found that only a very small power input is required to get definite variations of anode or output current. The construction is such that the device may be of a very small size for a given power or conversely a substantially increased power is provided for 40 a given size of tube. On account of the small size the construction is cheap and very easy to free from deleterious gas. As the volume of metal employed is very small, the tube is unusually stable since there is less 45 possibility of harmful gas being given off. So far as I can ascertain, the device is much more sensitive than any other vacuum tube device corresponding in size or cost.

50 While the tube as thus far described is operative, I find that the operation is much more uniform and stable when a ventilated shield such as 30 is employed. This shield is preferably of glass which is transparent so that the degree of incandescence of the 55 filament and the condition of the tube may be readily observed. One or more holes or perforations such as 31 should be provided so as to ventilate the shield. The shield serves to maintain all parts of the tube at 60 substantially the same temperature and thus prevent variations in the operation which might occur if drafts were allowed to blow upon the tube and alter the temperature of one part or another relative to the other 65 parts.

By the use of the external anode and control electrodes in combination with the internal equalizer, I am able to utilize the heated filament for the production of novel effects of current transfer and control which are radically different from those obtained by the use of internal anode or control electrodes.

I claim:

1. In a construction of the character described, a tube, an internal cathode, an external anode surrounding one part of the cathode, an external control adjacent another part of the cathode and spaced apart from the anode and an equalizer inside of the tube having a portion interposed between the control and the cathode and another portion connected with the first portion and interposed between the cathode and the anode. 75

2. In a construction of the character described, a tube, an internal electrode having two portions in series disposed longitudinally of the tube, an anode on the outside of the tube adjacent one portion of the inner electrode, a control on the outside of the tube adjacent the other portion of the inner electrode, and an equalizer on the inside of the tube having portions interposed between the inner electrode and the anode and control respectively. 85

3. In a construction of the character described, a tube, an inner electrode, two outer electrodes on the tube spaced apart from each other, and an equalizer supported inside of the tube between the inner and outer electrodes and separated from the inner and outer electrodes. 100

4. In a construction of the character described, a tube, a filament inside said tube, a plexus surrounding one portion of said filament inside the tube, an annulus surrounding another portion of the filament inside the tube and connected to said plexus, an anode, and a control element outside the tube. 105

5. In a construction of the character described, a tube, a filament inside said tube, a plexus surrounding one portion of said filament inside the tube, an annulus surrounding another portion of the filament inside the tube in contact with the inner wall of the tube and connected to said plexus, an anode in contact with the tube, and a control element outside of the tube. 115

6. In a construction of the character described, a tube, an internal filament cathode, an external cylindrical anode surrounding one part of the cathode, an external annular control surrounding another part of the cathode and spaced apart from the anode and an equalizer inside of the tube having an annulus interposed between the control and the cathode and a plexus electrically connected with the annulus and interposed between the cathode and the anode. 125

7. In a construction of the character described, a tube, an internal electrode having two portions in series disposed longitudinally of the tube, an anode embracing the outside of the tube adjacent one portion of the inner electrode, a control embracing the outside of the tube adjacent the other portion of the inner electrode, and an equalizer on the inside of the tube having a portion in contact with the tube between the inner electrode and the anode and another portion between the inner electrode and the control. 60
8. In a construction of the character described, a relatively long tube of small diameter, an inner electrode, two outer electrodes on the tube spaced apart from each other, and an equalizer supported inside of the tube between the inner and outer electrodes, 65 and having a non-perforated portion and a plexus respectively co-acting with the two outer electrodes. 70
9. In a construction of the character described, the combination of a tube, an internal electrode, two electrodes spaced apart from each other on the outside of said tube and a ventilated transparent shield surrounding said tube and said external electrodes for maintaining uniformity of conditions but to permit observation of the tube. 75
10. In a construction of the character described, the combination of a tube, an internal electrode, two electrodes spaced apart from each other on the outside of said tube and a ventilated transparent shield surrounding said tube and said external electrodes for maintaining uniformity of conditions but to permit observation of the tube, an equalizer surrounding said electrode inside the tube. 80
11. In a construction of the character described, the combination of a tube, an internal filament, two electrodes spaced apart from each other and surrounding the outside of said tube and a ventilated shield surrounding said tube and said external electrodes but spaced apart therefrom for maintaining uniformity of conditions but permitting observation of the tube. 85
12. In a construction of the character described, a tube, a divided filament inside said tube, a plexus adjacent and co-operating with one portion of said filament within said tube, a conducting member adjacent and co-operating with another portion of the filament inside said tube and connected to said plexus, an anode adjacent said plexus and a control element adjacent said conducting member but on the outside of said tube. 90
13. In a construction of the character described, two filamentary members connected together in series, a plexus adjacent and co-operating with one of said members, an imperforate element adjacent and co-operating with the other member and connected to said plexus, an anode adjacent said plexus and a control element adjacent said imperforate member. 95
14. In a construction of the character described, a filament, a plexus surrounding and co-operating with one portion of said filament, an annulus surrounding and co-operating with another portion of said filament and connected to said plexus, an anode adjacent said plexus and a control element adjacent said annulus. 100
15. In a construction of the character described, a tube, a filament extending longitudinally of the tube and supported at one end of the tube, a conductor supported at the same end of the tube, a plexus carried by said conductor surrounding one portion of said filament, and an annulus supported at the other end of said conductor and surrounding another portion of said filament. 105
16. In a construction of the character described, a tube, a filament extending longitudinally of the tube and supported at one end of the tube, a conductor supported at the same end of the tube, a plexus carried by said conductor surrounding one portion of said filament, an annulus supported at the other end of said conductor and surrounding another portion of said filament, and external electrodes respectively surrounding said plexus and said annulus. 110
17. In a device of the character described, a vacuum tube, an internal filament, an electrode on the outer surface of the tube, and a ventilated shield surrounding the tube and the outer electrode but spaced apart therefrom for maintaining substantial uniformity of conditions during operation of the device but permitting observation of the tube. 115
18. In a device of the character described, a vacuum tube, an internal cathode, an anode on the outer surface of the tube adjacent the cathode, and a ventilated shield surrounding said tube and its anode to prevent fluctuation of temperature and to permit observation of the condition of the tube. 120

HAROLD POTTER DONLE.
